PAPER BAG AND THE LIKE

José Daniel Errecaburde, Buenos Aires,
Argentina

Application January 5, 1942, Serial No. 425,689

1 Claim. (Cl. 229—62.5)

This invention relates to improvements in paper bags and the like, for sacking pulverulent or granular goods in general, and an essential object of the invention is to provide bags of said kind with certain novel structural improvements which will assure a perfectly tight seal of the same.

The improvements which form the object of this invention may be applied to bags formed by two or more superposed sheets or layers of paper or similar material and consist in providing one or more of the layers which form the internal lining or layer of the bag, with a suitable valve means, made integral with the body of the same and adapted to be obturated by a tubular valve, also formed integral with the aforesaid elements, and providing, in turn, one or more of the layers which form the outer lining or cover of the bag, with a flap, also integral with said latter layers and designed to be applied or affixed by cementing or otherwise, to the mouth of said tubular valve, so as to obtain a perfectly tight seal of the bag and thereby assure the indefinite keeping of the product contained in the bag.

This latter particular feature allows of conveniently using a novel type of bag for sacking grain and similar goods, since the tight seal of the bag not only prevents the contents from becoming infested with weevils, moths or other parasites, but also assures the destruction, by asphyxia, of any insects liable to get into the grain while being bagged.

A further advantage of importance of the novel type of bag in accordance with this invention consists in that the sealing flap of the tubular valve means also operates to effectively prevent the contents of the bags from being tampered with.

The invention also views other objects which will become apparent from a consideration of the following specification.

In order that this invention may clearly be understood and readily carried into practice, a preferred embodiment of the same has been shown by way of example in the illustrative drawings annexed to this specification. In said drawings:

Figure 1 shows an upper plan view of a blank designed to form the internal layers or lining of the improved type of bag, provided to that end with the necessary elements for forming the corresponding tubular valve means, of one single piece, in accordance with this invention.

Figure 2 illustrates the manner of assembling the internal body part or lining of the bag and the respective tubular valve means.

Figure 3 is a partial detail which illustrates the position assumed by the tubular valve when filling or emptying the bag.

Figure 4 is a diagrammatic detail which illus-

trates the position assumed by the internal body or lining of the bag after the tubular valve has been submitted to a first folding step in an inward direction.

5 Figure 5 shows an upper plan view of the blank for forming the external layers or covering part of the novel type of bag, and of the flaps which are to form the tight seal of the tubular valve means.

10 Figure 6 is a detail view which shows the position assumed by the sealing flap when applied on the mouth or entrance opening of the tubular valve.

Figure 7 illustrates another diagrammatic detail of the position assumed by the internal body part or lining of the bag after the tubular valve means has totally been folded inwards, and,

15 Figure 8 shows the improved bag after sealing, ready for storage or transport.

20 In all the said figures, the same numbers of reference have been used to indicate like or corresponding parts.

In the embodiment described and shown, it has been assumed that the bag in accordance with this invention consists of an internal lining or layer of paper or similar material, and an outer layer or cover, also of paper or the like, designed to fit or apply by superposition on the former layer, so as to form one single body, although, as above stated, the number of elements used to form one or both of said layers, may vary in accordance with the conditions required for strengthening the bag or adapt the same to any particular conditions of use.

25 35 In Figures 1 to 4 and 7 are shown the several elements which form the internal layer or lining; in the form of construction illustrated in the drawings, said elements substantially consist of a sheet A of paper or similar suitable material,

40 of rectangular shape, in which a number of folds or weakening creases 1 are formed, arranged longitudinally with regard to said sheet, so as to form the contour of the rectangular sides 2 and 3; from the upper and lower edges of either 45 sides or surfaces 2 and 3, small flaps 4 and 5, respectively, extend, adapted to fold along the weakening creases 6, formed in a longitudinal direction at the upper and lower margins of said surfaces.

50 With reference to Figure 1 it will also be seen that from the upper edge of two of the surfaces 3 and part of the surface 2, an extension B extends, substantially of rectangular shape, in which are formed weakening folds or creases 7,

55 one of which is arranged to correspond with one of the weakening creases first referred to, and another transversal folding or weakening crease 8, so that on said extension B, the rectangular spout surfaces 9 and wings 10, and the trapezoidal surfaces 11 will be formed, of which the

two latter are separated from the surfaces 2 by two folding lines or weakening creases 12 which converge in an oblique direction toward a suitable point on the central line 1.

From the lower edge of one of the surfaces 10 extends a flap 13, adapted to be folded along a weakening crease 14, while from one of the lateral margins of one of the surfaces 3, another flap 15 extends, adapted to fold along one of the longitudinal weakening creases 1.

In Figures 5, 6 and 8, the elements designed to form the outer layers or cover of the bag are shown; in the form of construction represented, said elements consist of a sheet C, also of paper or similar material and of a shape and dimensions adapted to those of the sheet A, first above described. Said sheet A is also provided with weakening lines 1' which form the surfaces 2' and 3', and the lateral flap 15' and the other flaps 4' and 5', adapted to fold along the folding creases 6', said lines, flaps and surfaces being so arranged as to enable the same to exactly correspond, by superposition, with the similar elements of said sheet or blank A.

With reference to the drawings it will further be seen that from the upper edge of the surfaces 3', an extension D projects, of substantially trapezoidal shape, separated from the former by two converging weakening creases 16, and on said surface two more converging folds are provided which contour a central surface 17, of triangular shape, and two lateral flaps 18.

For assembling this type of bag, one or several of the sheets or layers A are placed in superposition with one or several of the sheets or layers C, so as to cause the elements 1, 2, 3, 4, 5, 6 and 15 of the former to coincide with the similar elements of the latter.

With the parts in this position, the sheets A and B are folded, respectively, along the longitudinal margins 1 and 1', so that the pairs of blanks will have their faces 3 and 3' collapsed in an inward direction, after which the flaps 4, 4' and 5, 5' and the external flaps 15 and 15' are affixed, by cementing or otherwise, to the internal surface of the opposite sides or faces.

The upper extension B of the sheet A is folded along the weakening lines 8, as indicated in Figures 2 and 3, so that the surfaces 9 and the flaps 10 will project outside from the bag and assume a sheathing position so as to form a tubular member which extends into the bag and constitutes a tubular valve, properly; after this, the flap 13 is folded against said body part, in the manner shown in detail in Figure 3. With the parts being placed in this position, the bag will be ready for being filled with grain or other goods to be sacked, which after due disinfection or ventilation are fed in by the outer part of the valve element formed, as above stated, by the surfaces 9 and flaps 10. When the bag has been filled, said valve is folded successively along a transversal crease indicated by the dot and dash line 19 and then folded obliquely, as indicated in detail respectively in Figures 1 and 4 and thereupon the thus folded end of said tubular element is inserted into the space formed between the surfaces 10, whereby the seal will have duly been established, in such a manner as to render the same invisible from outside, as indicated by detail in Figure 7. In this position, the extension D of the sheets C is applied to the opening thus formed, so that the central surface 17 of said extension will be placed opposite to said opening,

whereupon the flaps 18 are secured by cementing or otherwise, to the lateral and outer surfaces of the bag, as may be seen by reference to Figure 8. This being done, the bag will be effectively and tightly sealed.

From the foregoing description it will have been understood that the conditions of safety of the seal obtained by the folding of the tubular valve and the operation of the extension D, in combination with the impermeability of the paper used in the manufacture of the bag, will set about within the same a condition of absolute tightness, thus allowing of the convenient keeping of the grain or other product contained in the bag, for any desired length of time.

Besides this important advantage, this novel type of bag allows of efficiently isolating the product contained therein, from any atmospheric agents, thereby preventing the contamination of the contents by impurities liable to filter through the meshes of hessian bags, or carried by the grain handled in bulk, and the consequent infection of certain kinds of grain which frequently arrive at the port of destiny in badly fermented conditions.

From the foregoing, the nature of this invention will have clearly been understood and no further details will be required by those skilled in the art.

It will be evident that several modifications of construction and detail may be introduced without departing from the scope of this invention, as clearly set forth in the claiming clauses hereto annexed.

Having now particularly described and determined the nature of this invention and in what manner the same is to be performed, I declare that what I claim and desire to secure by Letters Patent is:

A bag or the like, comprising, a substantially rectangular inner lining, a substantially rectangular outer casing enveloping said inner lining, said lining and casing each having inwardly folded gusset-type sides, a flattened tubular spout portion connected with said lining and having its longitudinal axis disposed at right angles to one side of the lining below the top edge thereof, said spout having its inner end opening into the space formed by the lining and having its outer end initially projecting beyond the limits of the outer casing, whereby, to close said inner lining said outer end of the spout may be folded transversely inwardly upon itself and then folded obliquely inwardly upon the first mentioned fold to provide an inner seal whose outer folded edge is disposed at a substantially 45° angle within the included angle formed by the projected planes of the top and one side of the bag, and an outer sealing extension on the outer casing at the end of the gusset-type side thereof adjacent the folded spout, said extension having marginal sealing flaps whose lower ends are cut in converging planes which intersect each other at right angles below the top of the casing and at the fold line of said gusset-type side with which the extension is connected, whereby the base of said extension may be swung inwardly along lines defined by the aforesaid last mentioned planes to cover the inner seal formed by the folded spout and the flaps may be folded downwardly and adhesively connected to the outer sides of the casing to provide an outer seal for the bag.

JOSÉ DANIEL ERRECABORDE.
